UNITED STATES PATENT OFFICE.

THOMAS A. DE VILBISS, OF TOLEDO, OHIO, ASSIGNOR TO THE DE VILBISS MANUFACTURING COMPANY, OF TOLEDO, OHIO, A CORPORATION OF OHIO.

ATOMIZER.

No. 864,456.

Specification of Letters Patent.

Patented Aug. 27, 1907.

Application filed December 10, 1906. Serial No. 347,152.

To all whom it may concern:

Be it known that I, THOMAS A. DE VILBISS, a citizen of the United States, and a resident of Toledo, in the county of Lucas and State of Ohio, have invented certain new and useful Improvements in Atomizers; and I do hereby declare the following to be a full, clear, and exact description of the invention, such as will enable others skilled in the art to which it appertains to make and use the same, reference being had to the accompanying drawings, and to the figures and letters of reference marked thereon, which form a part of this specification.

My invention relates to atomizers of the class particularly designed for the reduction of liquids to the form of spray for inhalation or for application to the throat or nasal passages, and for other purposes.

The object of my invention is the provision in an apparatus of this nature of a valve adapted to be moved to either open or close the liquid and air channels thereof whereby the bulb or actuating agent may be operated or the apparatus turned in any position without the escape of fluid either in liquid or spray form therefrom, thus adapting the apparatus for use by travelers or the like, as it can be packed without removing the liquid therefrom and without liability of its leaking and soiling other articles packed therewith.

The operation, arrangement and construction of the parts of the invention are fully described in the following specification, and illustrated in the accompanying drawings, in which,—

Figure 1 is a perspective view of an atomizer of the vacuum type embodying my invention. Fig. 2 is an enlarged central horizontal section of the vessel cap and associated valve, with the latter in open position. Figs. 3 and 4 are similar views with the valve plug removed in the former and in closed position in the latter. Fig. 5 is a central vertical section of the cap and valve plug, with the latter in open position. Fig. 6 is a bottom view of the cap and valve plug assembled. Fig. 7 is a vertical section on the dotted lines $x-x$ in Figs. 2 and 5. Figs. 8 and 9 are similar sections, respectively, on the dotted lines $y-y$ and $z-z$ in Fig. 5, the former showing the cap secured to the neck of a liquid receptacle. Fig. 10 is a view of the side of the valve plug disposed toward the nozzle when the plug is in open position.

Referring to Figs. 1 to 10 of the drawings, 1 designates the liquid receptacle of an atomizer; 2 a plug or cap for closing the neck thereof and which is shown as being threaded to a collar 3 secured to the receptacle neck; 4 the nipple to which the tube of the air-supply bulb 5 is attached, and 6 the nozzle. This nozzle has direct communication with the air-supply bulb through the air-tube 7, channel 8 in the cap-head, and nipple 4, and with the interior of the receptacle through the tube 9, channel 10 in the cap-head and the interior tube 11,

the lower end of which latter is intended to be submerged in the liquid contained in the receptacle.

In carrying out the idea of my invention I provide the cap-head with a transverse tapered cylindrical opening 12 at substantial right angles to and intercepting the channels 8 and 10 therein, as shown, and mount therein a tapered valve-plug 13. This plug is prevented from removal from its casing in any suitable manner, as by threading a nut 14 to its reduced end, and to facilitate its turning has its other end formed with a suitable finger-grip, as shown. Provided through the plug 13 are the straight channel 15 and angled channel 16, the former registering at its ends with the separated portions of the channel 8 in the cap-head, as shown in Figs. 2 and 7, and the latter registering at its ends with the separated portions of the channel 10 in the cap-head, as shown in Figs. 2 and 9, when the plug is in what may be termed open position relative to the cap, thus opening communication between the air-supply means and nozzle 6 in the one instance and the interior of the receptacle 1 and nozzle 6 in the other instance. Extending laterally from the channel 15 of the plug is a needle-point aperture or duct 17, which, when the plug is in open position, is intended to communicate with the interior of the receptacle through the small channel or duct 18 in the cap-head, as shown in Figs. 5 and 7. The channel or duct 17 in the plug has its outer end enlarged, as shown at 19, to insure its registering with the channel or duct 18 when the plug is turned to open position. The purpose of the channel 17-18 is to permit a small portion of the air passing through the channel 8-15 in the cap-head and plug to enter the receptacle above the liquid therein, thus creating a pressure on its surface and effecting a heavier ejection of spray from the nozzle 6 than would be occasioned by the air suction alone. As the provision of this communication between the air-supply and the interior of the vessel has a tendency to flood the tube 9 and eject the liquid in stream rather than spray form it is only intended for use in emergencies, such, for instance, as cleaning the liquid tubes should they become clogged, and the pressure thus created in the vessel is normally released therefrom through the vent channel 20. This channel is provided through the cap-head and plug, as shown in Fig. 8, and opens communication between the interior of the vessel and the atmosphere. By closing the outer end of the channel 20 with the thumb or finger the air pressure within the vessel exerts itself upon the liquid and causes the ejection thereof from the nozzle 6.

Having thus described my invention, what I claim as new and desire to secure by Letters Patent, is,—

1. In association with the receptacle and the air and liquid passages of an atomizer, a valve member, which, when in open position, has a channel in register with the

105

110

air-passage, a channel in register with the liquid passage, and a channel opening communication between the interior of the receptacle and the atmosphere.

2. In association with the receptacle and the air and liquid passages of an atomizer, a valve member which, when in open position, has a channel in register with the air-passage, a channel in register with the liquid passage, a by-pass from the air-channel into the receptacle, and a channel opening communication between the interior of the receptacle and the atmosphere.

3. In combination in an atomizer, a receptacle, a cap for closing the mouth of the receptacle and having air and liquid passages therethrough and a transverse opening intercepting said passages, and a valve-member mounted in

said opening and when in open position having channels in register with the air and liquid passages, a restricted by-pass from the air-channel into the receptacle, and a vent channel opening communication between the interior of the receptacle and the atmosphere.

In testimony whereof I have hereunto signed my name to this specification in the presence of two subscribing witnesses.

THOMAS A. DE VILBISS.
